CLOCK

Edward P. Cheslock, R.D. 1, Lincoln
University, Pa. 19352

Filed Sept. 3, 1970, Ser. No. 24,825

Term of patent 14 years

Int. Cl. D10—01

U.S. Cl. D42—7

FIG. 1 is a pictorial view of a clock, showing my new design.

FIG. 2 is a front elevational view thereof.

FIG. 3 is a back elevational view thereof.

FIG. 4 is a top plan view thereof.

FIG. 5 is a side elevational view thereof.

I claim:

The ornamental design for a clock, as shown.
